COMBING MACHINE

Odus C. Hinson, Cramerton, N. C., assignor, by
mesne assignments, to The Terrell Machine
Company, Charlotte, N. C., a corporation of
North Carolina

Application January 4, 1945, Serial No. 571,231

35 Claims. (Cl. 19—116)

1

This invention relates in general to fiber combing machines, and in particular to cotton combing machines operating on the principles of the well-known Heilmann comber. The invention contemplates a comprehensive reorganization of the structure, functions, and motions of the entire machine, in the effort to produce substantial improvement in its efficiency. As heretofore, this machine is of course designed to operate upon cotton fibers having average staple lengths varying throughout the range customarily used in the production of combed yarns; this range is usually between $1\frac{1}{2}$ inches and $1\frac{3}{4}$ inches, although for finer yarns special cottons having an average staple length on the order of $1\frac{1}{2}$ inches are occasionally combed with it.

A leading object of the invention is to increase the production of the comber in terms of pounds of combed cotton produced per hour, whereby material savings to the mill and in the initial cost of the machines and floor space required, and in the power, upkeep and attendance will be effected.

Another leading object of the invention is to improve the quality of the combed sliver produced by the machine, so as to make the yarn spun from such sliver cleaner and stronger than heretofore, such improvement residing not only in more complete removal of short fibers and neps and trash while retaining more of the long fibers, but also in the attainment of more uniform fiber density in the combed sliver at all points in its length, whereby better drawing and a reduction in the drawing and doubling processes will be attained. Further objects are to simplify the machine, both for the purpose of reducing the cost of building the machine itself, and for the purpose of facilitating its operation, its setting and adjustment, and its servicing; and to eliminate or reduce wear and thus the need for repairs and replacement of parts. Still further objects are to provide improved facilities for salvaging and disposing of the waste produced in the operation of the machine; and to prevent or reduce to a minimum the production of fly.

To these ends, the invention is based on the principle of making the combed sliver uniform in thickness or fiber density at all points in its length in the act of piecing up at the detaching roll. This is attained by overlapping the successive combed tufts each for more than half its length in such manner that the desired uniform thickness or fiber density is secured at this location, and preferably through making the combed web, lap, or sheet of the thickness of two, three,

2

or more combed tufts, or the equivalent thereof, as may be decided upon as the standard in advance, throughout all points in its length. This is in distinct contrast to the system of piecing-up employed in all prior combing machines with which I am acquainted, in which each successive combed tuft is overlapped onto the preceding combed tuft for a distance materially less than half the length of the preceding combed tuft. Since the combed tufts in prior practice were relatively short, and since the end portions of such combed tufts are necessarily sharply tapered off and thinned down by the nature of the detaching action, and only these feathered end-portions of reduced fiber density are brought into overlapping relation in prior machines, the resulting combed web in prior machines is of single ply construction and maximum thickness or density at midlength of each combed tuft, and of 10 2-ply nature but of greatly reduced fiber density throughout the zones of overlap between each two successive combed tufts. This variation in fiber density is what gives the combed web in the pan of the prior Heilmann type combers its 15 conspicuous and characteristic transversely barred or striped appearance.

The overlapping of each tuft for more than half its length onto the preceding and following tufts which is employed according to the invention to create the predetermined consistent 2, 3, 20 or more, ply thickness of the combed web, makes the beginning of each combed tuft add and the ending thereof detract a much lesser percentage to or from the thickness of the combed web than in 25 prior arrangements, imparting an inherent and visible uniform density to the combed web which persists throughout all subsequent processes into the finished yarn, giving more uniform and 30 stronger yarn and stronger cloth, with greatly 35 reduced doubling and drawing, and with marked 40 reduction in end breakage in all processes.

As relates to production, a substantial amount of force is required to be exerted on the successive tufts by the detaching rolls in order to pull 45 out and draft the stock and detach the tuft. There is thus a limit to the number of fibers the detaching rolls can draft at a time, beyond which limit the rolls will be overloaded and slip, and will not detach a proper and uniform tuft, and 50 the fibers which escape are left hanging from the fringe protruding from the nippers and are torn off as waste by the needle segment on the next combing action. Consequently, the theory and practice in prior combers has been that to attain good combing it was necessary to "comb light" by

restricting the weight of lap fed to the comber to a maximum of around 850 grains per yard of 12-inch lap and an average of 700 grains per yard in ordinary practice, feeding such lap at the rate of around .18 inch per nip, and producing a relatively short combed tuft never exceeding 2½" in length which has been subjected to a draft of around 7 times by the action of the detaching rolls, with the production of a 6-head comber limited to around 20 pounds per hour of combed cotton. In these machines, when the lap weight or the feed is increased in the effort to increase production, the combed tufts become too thick and overload the detaching rolls, as well as giving rise to other difficulties impairing production.

In accordance with the invention, however, my multiply combed lap is formed of combed tufts which preferably are subjected to a draft on the order of 20 or more times by the action of the detaching rolls. This makes it possible to double the weight of the lap fed to the machine, and thus to double the production of the machine at the standard number of nips per minute without need to increase materially the length of the feed, which would reduce the combing action of the half-lap, and without overloading the detaching rolls and causing them to slip, since fewer fibers are seized and drawn forward at a given instant. Because the combined tuft is extended three or more times as far as in prior machines, it requires less effort to draft it. Because the combed tuft is thinner, and fewer fibers are pulled through the top comb at any given instant, the top comb is able to do a more complete job of removing the neps and foreign matter from the tail portions of the fibers making up the combed lap.

To facilitate the great increase in the draft, improvements have been made in the nipper jaws enabling them to grip the fibers much closer than previously to the path of the needle points on the half-lap, so that more of the length of each fiber is combed by the half-lap before going forward and more short fibers and fewer long fibers are removed, leaving less of such length to be combed by the top comb, permitting the top comb to enter the combed fringe closer to the bite of the nippers and so leaving a longer fringe in front of the top comb, which makes it possible to give this fringe the long forward motion by the combined action of the feed roll and the forward swing of the swing frame which is helpful during detaching in order to produce the long draft of the invention. In prior structures, the shortness of this fringe forward of the top comb prevented any great amplitude of forward movement of the top comb after entering the fringe, as such movement would bring the top comb into collision with the detaching rolls; and hence the prolonged forward movement of the combed fringe after seizure by the detaching rolls which facilitates high production was impossible. The long forward movement during detaching, coupled with an increased rate of surface travel of the detaching rolls, causes the leading ends of the fibers of the fringe to be seized progressively throughout a longer distance of such movement and drawn forward ahead of the adjacent but lagging fibers, thereby lengthening the draft.

By reason of the increased length of the portion of each fiber combed by the half-lap before release by the nipper jaws, not only is less full-length and usable fiber thrown down as waste, but the half-lap subjects each fiber to a greater number of strokes before release, making it pos-

sible to use fewer and hence coarser needles in the standard number of rows on the half-lap, reducing clogging and failure to comb properly. Being coarser, the needles can be made thicker and stronger, and thus can be made longer, which in turn permits the increase in the weight of the supply lap while still effecting proper combing thereof.

I have found that the increase in the weight of the supply lap made possible through the features of my invention in itself attains an important advantage. By increasing the weight of the supply lap, which I have successfully done up to 1500 grains per yard of 12 inch lap, or substantially double the weights employed in prior combers, the density and strength of the supply lap coupled with the progressive seizing of only the endmost fibers of the combed fringe by the detaching rolls in each detaching action, causes the stock itself to wipe the short fibers, neps and trash off from the tails of the fibers caught and pulled forward by the detaching rolls, these short fibers, neps and trash being left behind in the supply lap and removed therefrom by the half-lap during the combing of the next tuft.

To create the multiply lap and to produce and handle the combed tufts of greatly increased length which make possible the increase in the production of the machine, substantial increases are made in the surface travel and velocity of the detaching rolls, and in the diameter of the bottom steel detaching roll, the latter increase aiding in supporting the longer extent of combed lap fed back for the piece-up. A feature of improvement in this connection resides in employing only three rolls to perform the detaching and piecing-up operation, while eliminating all oscillating or bodily movement of any of these rolls, with consequent simplifying of structure, operation, and adjustment, and with the function of one of the rolls reduced merely to forming the combed lap to the curvature of the bottom steel detaching roll so that it will curve downward in front of and out of contact with the combing cylinder in piecing-up, and also to compacting or calendering the tufts into a coherent combed lap. Novel provision is also made for preventing contact of the combed tuft with the combing cylinder when fed back for piecing-up. Improvements have also been made in the shaping of the cams operating the detaching rolls and the swing frame to enable the combing and drafting of tufts of increased length.

Extensive simplification of the structure, motions, and actuation of the working parts in addition to those already detailed, and even of the fixed structural parts of the device, as well as simplifications in the adjustments and improvements in the bearings and provisions for lubrication thereof and the elimination of troublesome points of wear, leading to economies in the cost of construction and operation, have been made as set forth hereinafter.

A novel pneumatic waste salvage disposal system is provided, continuously removing all waste and fly produced in the combing and detaching actions and depositing it directly in the waste bin; improved means for examining the waste to determine the percentage of fiber being removed in the combing is also provided, all as set forth hereinafter.

Other objects of the invention, and the manner of their attainment, are as set forth in the following description.

Illustrative embodiment of the features of the invention are shown in the accompanying drawings in which:

Fig. 1 is a front elevation of a 6-head comber, with two of the heads omitted and with the main working parts present in each comber head shown in isolated relation in the successive comber heads for clarity.

Fig. 2 is an elevation of the left-hand end of the machine of Fig. 1.

Fig. 3 is a vertical section through one of the comber heads at line 3-3 in Fig. 1.

Fig. 4 is a vertical section similar to Fig. 3, showing in detail the swing frame and its working parts and their relation to the combing cylinder and the detaching rolls, and the actuation of the nippers and the top comb.

Fig. 5 is a view in vertical section on line 5-5 of Fig. 1, showing the drives for the detaching rolls, the lap-feed, and the stripping brush.

Fig. 6 is a section on line 6-6 of Fig. 1, showing the drive for oscillating the swing frame, and also the actuation of the oil pump.

Fig. 7 is a view in front elevation showing certain of the parts of Figs. 5 and 6.

Fig. 8 is a section on line 8-8 of Fig. 5, giving details of the differential gearing driving the detaching rolls.

Fig. 9 is a section on line 9-9 of Fig. 8.

Fig. 10 is an elevation of the planetary gear plate of the differential gearing of Fig. 8.

Fig. 11 is a section on line 11-11 of Fig. 10.

Fig. 12 is a diagrammatic showing of the relationship of the successive combed tufts which form the multiply combed lap.

Fig. 13 is a diagram showing how the multiply combed lap is produced.

Fig. 14 is a side elevation of the improved nipper jaws, combing cylinder, and feed roll, on an enlarged scale.

Fig. 15 is a detail in side elevation showing the quick release pressure means for weighting the detaching rolls.

Fig. 16 is a view of certain of the parts of Fig. 5 in front elevation.

In the front elevation of Fig. 1, the combing cylinder carrying the half-lap is indicated at 1, the stripping brush which clears the waste from the needles 3 of the half-lap being indicated at 5, and the other parts which cooperate in the combing action being omitted from this particular head for clarity, being shown separately in connection with the other heads. Thus, the bottom detaching roll is indicated at 7 in connection with the next head to the right thereof, together with a housing 9, generally rectangular in plan, which wholly surrounds the stripping brush 5, includes the lower half of the combing cylinder, and approaches closely to the surface of such cylinder at the rear of the machine and to the periphery of bottom detaching roll 7 at the front of the machine, whereby all fly produced by the combing action is carried down and away from these rolls by a downwardly traveling air current induced within housing 9 as indicated hereafter.

At 11 is indicated a swing frame carrying the nippers and the feed roll, this frame being fixed on a rockshaft 13 which is continuous through all the heads. The top comb is indicated at 15, being pivotally mounted to swing back and forth on studs 17 in connection with the uprights 19 located at each side of each head. As indicated, all of these members are present in each head of the comber, as shown in Figs. 3 and 4, where they

work together in performing the combing action in accordance with the basic principles of the Heilmann type comber.

In the machine of the invention, an outstanding feature of novelty is the use of the rocking movement of small amplitude of rockshaft 13 to swing the swing frame 11 back and forth, and from this simple motion alone to operate the nippers and the feed roll, to bring the stock held by the nippers into combing relation with the needles of the half-lap, to lower the top comb into the combed fringe, to feed the head ends of the combed fibers into the nip of the detaching rolls, and to drive the lap rolls feeding the uncombed stock into the machine, all in properly timed and co-ordinated relation.

The swing frame 11 of each head comprises two pendent arms 21 each fixed by its hub 22 upon rockshaft 13 by a pair of set screws 23. To the inward surface of each of these arms there is attached by cap screw 25 the upwardly extending end of a heavy lug 27 formed integrally at each end of a heavy cross-member 29 of roughly triangular section with rounded upper apex, the inclined forward surface of which member 29 serves as a guide for the descending lap. The lower jaw 31 of the nippers, the cushion plate, so-called, is applied within a rabbet formed in the under surface of the member 29, being secured by cap screws 33 passing through slots 35 therein, so that the lower jaw may be adjusted back and forth transversely of member 29 by operation of set screws 37 bearing against the rear edge of lower jaw 31. Two downwardly inclined brackets 39 extend rearwardly from cross-member 29 at each end thereof, having hubs 41 in which is rotatably mounted a shaft 43 to which are affixed the hubs of two arms 45 which carry the top nipper jaw 47, such arms reaching up and forwardly over the member 29, just inside lugs 27, with the nipper jaw bolted to a rabbet cut in the end of each arm by screws 49. Preferably, one arm 45 has special means for screw adjustment of its angular position about shaft 43, to facilitate adjusting the upper and lower nipper jaws into exact parallelism, as shown in Fig. 14.

To actuate the nippers, an arm 51 is fixed on the end of shaft 43 outside one bracket 39, the upper end of which arm is pivoted at 53 to a clevis 55 on one end of a threaded link 57 passing through a bearing 59 on a fixed part 61 of the frame of the machine, with adjustable stop-nuts 63 applied to the rearward end of the link and with an expanding coil spring 65 confined between the bearing 59 and stop-nuts 63 located at an intermediate point in the length of link 57. Thus, as the swing frame 11 swings back, i. e., toward the right in Figs. 3 and 4, spring 65 tends to hold the upper end of arm 51 from moving rearwardly while its lower end attached to shaft 43 moves rearwardly, thus rotating shaft 43 and arms 45 counter-clockwise to force top nipper jaw 47 yieldingly downward against bottom jaw 31, as shown in Figs. 4 and 14, to grip the intervening lap while the fringe of fibers protruding from the jaws is combed by the needles 3 of the needle segment of combing cylinder 1. When the swing frame swings forward, stop-nuts 63 bring up against bearing 59, causing link 57 to detain the upper end of arm 51 while the lower end thereof moves forward, thus causing a reverse rotation of shaft 43 which lifts top nipper jaw 47 well away from bottom jaw 31, as shown in Fig. 3, permitting feeding of the uncombed lap.

The motion of pivot 53 in space is so slight that there is practically no movement of link 57 through bearing 59, and thus the wear on the parts producing the opening and closing of the nipper jaws is practically nil. Adjustment of stop-nuts 67 along link 57 to increase or reduce the tension of spring 65 completely controls the force with which the jaws close upon the lap. Adjustment of stop-nuts 63 along the link determines the moment of opening of the nipper jaws. When properly adjusted, nuts 63 need not leave their contact with the end of bearing 59 more than $\frac{1}{8}$ inch.

Departing from prior practice, the main grip of the nipper jaws upon the fibers held between them is exerted between the vertical rearward face of the pendent lip 69, Fig. 14, of top nipper jaw 47 and the opposing edge 71 of the bottom jaw 31. Some holding effect is of course obtained between the top surface of bottom jaw 31 and the rearwardly extending opposing surface of the top jaw 47 as heretofore; but the rearward surface of lip 69 and of the opposing edge of bottom jaw 31 are purposely cut with a slight downward and forward bevel, so that when closed upon the intervening lap the jaws wedge together and the main gripping pressure is exerted in the direction of the plane of lower jaw 31. Adjustment of lower jaw 31 in such plane by means of screws 33 and 37 is provided to insure such grip. By making the forward edge of lower jaw 31 relatively thin and by shortening the pendent lip 69 of the upper jaw to substantially the same length as the thickness of such forward edge, the fibers forming the fringe protruding from the closed jaws are gripped much closer than heretofore to the path of the needle points on combing cylinder 1, thereby exposing more of the length of each fiber to the combing action of these needles before being released and drawn forward by the detaching rolls, and also retaining more of the desired full-length fibers which arrive at the nipper jaws in oblique relation to the direction of feed, thus resulting in both more complete removal of short fibers, neps and trash, and in better parallelizing of the fibers, helping to make possible efficient combing of a double-weight lap, coupled with greater economy of fibers of usable length. Also, by reason of such close holding, the top comb which should enter the fringe forward of the point where the half-lap needles terminate their action, can do so at points near the tails of the fibers thus combed, with important results which will be referred to later herein.

The nipper jaws close well before the swing frame 11 reaches its extreme rearward position of Fig. 4, and the leading rows of needles 3 of the half-lap enter the fringe held by the jaws while the latter are moving rearward and before they have reached their point of closest approach to the path of the needles. Thus the needles enter the fringe to a progressively increasing depth, during the passage of the first quarter of the half-lap, the leading rows making a shallow penetration and the following rows penetrating to full depth as the swing frame dwells at back center while the remaining three-quarters of the half-lap passes and combs the fringe. Thereby the cleaning out and untangling of the fibers is effected more gradually and progressively.

To the same end, the half-lap is extended to encompass one-third of the circumference of combing cylinder 1, so that the combing is prolonged throughout this fraction of the machine's cycle. The usual 17 rows of needles are prefer-

ably used. However, the fibers are gripped by the nipper jaws closer to the path of the needles and thus with the standard rate of feed of the stock of approximately $\frac{1}{8}$ inch each fiber is subjected to a greater number of strokes of the half-lap before being drawn forward by the detaching rolls. This factor, coupled with the gradual and prolonged nature of the combing action, makes it possible to effect thorough combing even of a lap of increased thickness with fewer and hence coarser needles having less tendency to clog and thus to fail to comb properly. With the needles thus set farther apart in the rows, they can be made thicker and hence of increased strength permitting them to be made longer than possible heretofore. Being longer, they can penetrate through and properly comb a thicker fringe, thus aiding in making possible the use of a supply lap of greatly increased thickness and weight.

The remaining two-thirds of the periphery of the combing cylinder is of smooth, polished metal and of substantially the same radius as that of the path of the needle points.

Feed roll 73 has coarse metal flutes, and is at least half again as large in diameter as in prior machines, to handle the double-weight lap without puckering. Its journals 75 are held in half-bearings formed in the end-portions of rockers 77 pivoted on screws 79 threaded into the lower portions of lugs 27, the rear extremities of these rockers being pivoted at 81 each to a clevis 83 whose end is threaded into a contracting coil spring 85 similarly attached to a plug 87 fixed on the end of a rod 89 equipped at its upper end with a handle 91, the rod having a portion 93 of reduced diameter normally reposing in the radial slot of a keyhole-shaped passage 95 through a bracket 97 extending from the back of the hub on arm 21 which encircles rockshaft 13. The supply lap fed to the machine is in the form of the usual roll 99, resting on flanged wooden rollers 101 of standard type, being unrolled from the bottom of roll 99 and following the path indicated by dot-and-dash line 102 over the front roller 101, over rockshaft 13, and thence between feed roll 73 and lower jaw 31, where it is gripped tightly and fed through the nipper jaws. In threading up, therefore, the feed roll pressure must be released, and for this purpose rod 89 is pushed rearward to disengage the shoulder at the top of reduced portion 93 from the keyhole slot to permit the rod's full diameter to descend through the circular portion of the keyhole, thus permitting the feed roll to be lifted and rotated manually to enter the lap thereunder. This done, the tension is restored by pulling upward and forward on handle 91 to put the parts back into the relation shown in Fig. 4.

The feed roll is actuated by means of a ratchet 103 fixed on one journal thereof beyond the rocker 77, the ratchet being engaged by a pawl 105 pivoted on stud 17 fixed in the machine frame, and which also supports the top comb 15, the shank of the pawl passing through a lug 107 on a hub 109 rotating on stud 17 and being adjustable up and down by means of nuts 111 to feed the ratchet one tooth during the forward swing of swing frame 11. Variation in the length of feed is attained when necessary by substituting a ratchet having more or less teeth. In practice, a feed of around .20 inch of lap per nip is commonly employed. The partial unwinding of the lap from around shaft 13 during the forward swing of the nippers supplies a certain amount of slack in the

lap for the feed. The main supply is as usual effected by the driving of lap rolls 101.

The novel top comb 15 comprises a comb plate 113 having needles set along its lower edge, such plate being secured by screws 115 to a carrier 117 provided at each end with a boss 119 into which is threaded a long headed screw-rod 121 which extends loosely through a sleeve 123 formed integrally with but inwardly of the plane of the end of a hub 125 which swings freely on stud 17. A link 127 pivoted upon a cap screw 129 threaded into a lug formed at each end of carrier 117 has a hook 131 formed in its rearward end which hooks over a pin 133 adjustably fixed in a slot 135 in a lug 137 extending forward from each arm 21 of the swing frame. Thus, a forward and backward swing is imparted to top comb 15 by the corresponding swinging movement of the swing frame as rockshaft 13 is oscillated. As the top comb swings about a different center, the path of the needle points of the top comb intersects that of the lower nipper jaw 31 and the needles enter the combed fringe being carried forward by the latter as indicated by the arcs in Fig. 4. Because the fibers have been held by the nippers at a point in their length which is very close to the point at which the half-lap needles have combed these fibers, the combed fringe is much longer than heretofore, on the order of half again as long. The top comb is set to enter the combed fringe close to the lower nipper jaw while still entering ahead of the beginning of the uncombed tail portions of such fibers, so that the comb enters the fringe more than half the length of the fibers back from the edge of the fringe. As a result, the extent of combed fringe in front of the top comb is substantially longer than in prior machines, which makes possible a prolonged feeding movement of this fringe into the nip of the detaching rolls, by the continued forward swing of the swing frame coupled with the rotation of feed roll 73, without collision of the top comb with the detaching rolls. This feature is of importance in making possible the long draft given to the combed tuft by the detaching rolls, as will be noted hereinafter.

The novel mounting of the top comb permits it to be easily swung up out of the way for threading up, cleaning, repairs, and other purposes. Thus, the two links 127 are merely unhooked from their pins 133, the comb is lifted slightly to clear the top detaching rolls, with attendant upward sliding of screw-rods 121 through sleeves 123, and the whole comb structure is then swung forward and upward over its axis of rotation on studs 17 so that sleeves 123 rest against the adjacent corners on the tops of hubs 22, the comb structure thus remaining out of the way until reinstated in working position by a reversal of these simple operations. The depth of penetration of the top comb and the location of its path of travel are adjusted by manipulation of screw-rods 121 up or down in bosses 119.

The detaching rolls include a bottom roll 7 having a fluted metallic surface and of substantially double the diameter previously used, being on the order of two inches in diameter so as to give more extended support to the long combed tufts when fed back for the piece-up. With this bottom detaching roll there are employed two top detaching rolls 8, 10, of half the size of the bottom roll, i. e., of substantially one inch diameter, covered with leather or other suitable flexible material, which work in fixed position and

have no bodily movement in space, except that they are yieldingly pressed down toward the surface of bottom roll 7 by spring weighting means enabling them to rise as the combed tufts enter between them and the bottom roll, such spring means being strong enough to insure a firm grip on the fibers introduced by the swing frame between top roll 8 and the preceding feed-back combed tufts sufficient to draw out the fibers and to detach the rear end of the combed tuft from the supply lap as the swing frame recedes.

A feature of the weighting means for top detaching rolls 8, 10, is the provision for instantaneously releasing the rolls from pressure and re-establishing such pressure. To these ends, as shown in Figs. 3, 15, and 16, a small stand 4 is affixed to a bracket 6 extending forwardly from the upright 19 at each side of each comber head, and a stud 12 is fixed in a hub in each stand. On each of these studs is pivoted a lever 14 having its upper arm pivotally connected by a bolt 16 to a clevis formed as a part of a yoke 18 which fits over needle bearings 20 positioned on the journals of top rolls 8, 10. The lower arm of each lever 14 terminates in an eye through which extends a rod 22 screwed into a boss on a hub 24 rotating on a rod 26 fixed in hubs in the ends of arms 28 which are pivotally mounted on studs 12 just outside the arms 14. Expanding coil springs 30 on rods 22 are confined between the eyed ends of levers 14 and the bosses on the associated hubs 24, so that when arms 28 and rod 26 joining them are swung clockwise in Fig. 15 the springs 30 are stressed to bias lever 14 in a clockwise direction, thus putting a downward pressure on each yoke 18 which is transmitted to rolls 8, 10, to press them downward against the surface of bottom detaching roll 7. To operate arms 28 in this manner, the left-hand one of such arms is continued upwardly to form a hand-lever 32, which is provided with a detent in the form of a spring-pressed plunger working in a boss 34 on the lever and engaging within a hole in the upper end of an extension 36 on stand 4. Thus, with the parts in the pressure applying relation shown, withdrawal of the spring plunger, by means of the knob 38, from engagement with the hole in extension 36 releases lever 32 and arms 28 for counterclockwise rotation, first under the push of spring 30 and thereafter by a manual pull forward on handle 32, the lock-nuts on rod 22 turning lever 14 to lift yoke 18 away from bearings 20, thus releasing the top detaching rolls for removal for cleaning, replacement, and other purposes. When these rolls are replaced, the pressure is reestablished by manually pushing handle 32 back into vertical position, the spring plunger sliding over a beveled surface on extension 36 in front of the hole and then snapping into the hole therein to hold the parts again in working position.

The studs 12 also form the pivots for the hubs 40, Fig. 16, of clearer-boards (not shown) which rest by gravity on top detaching rolls 8, 10.

Top rolls 8, 10, are rotated solely through frictional engagement with the combed tufts which intervene between them and the surface of roll 7 and which are fed back and forth by the rotation of bottom roll 7 in alternately opposite directions as shown in Fig. 13. Thus, as the swing frame swings forward, bottom detaching roll 7 starts to rotate counterclockwise in Fig. 4, starting slowly just before the leading fibers of the advancing fringe protruding from the nipper jaws reach the bite between rolls 7 and 8, and

thereafter accelerating rapidly, until it has made preferably 5 or more inches of surface travel. Top rolls 8, 10, rotate in clockwise direction for an equal amount of surface travel. Thus first the ends of the foremost fibers are grasped by rolls 7 and 8 and pulled forward, while the forward swing of the swing frame, with accompanying forward movement of the top comb, progressively feeds the leading ends of the succeeding fibers of the fringe into the nip of detaching rolls 7 and 8. The swing frame starts backward as detaching roll 7 completes its counterclockwise movement retracting the remaining fibers of the lap out of the reach of the detaching rolls and thus effecting the detachment of the combed tuft held by the detaching rolls from the supply extending through the open nipper jaws. As feed roll 73 has advanced the lap about $\frac{1}{2}$ inch during the forward swing, and the detaching rolls have progressively pulled forward the fibers of the combed fringe throughout nearly all the approximately 5 inches of their surface travel, an extension of the combed tuft of around 20 times is achieved. Because the combed fringe forward of the top comb is long, and the surface travel of the detaching roll 7 forward is long and rapid, the swing frame can continue its forward swing for a prolonged feeding period and thus feed fewer fibers at any given moment into the detaching rolls, even with a double-weight lap. Since the fibers whose leading ends are gripped by the detaching rolls at the instant of detaching also are pulled out from the fringe and form the rear end-portion of the detached tuft, the total length of the latter is on the order of $5\frac{1}{4}$ inches, depending on the promptness of entry of the fringe between the detaching rolls after the latter start forward and the length of staple which the machine is set to reject and to throw down as waste, this latter being determined as heretofore by the closeness of approach of the lower nipper jaw to the nip of the detaching rolls. On account of the relatively great extension of the tuft, even with 1500 grain supply lap the tuft is thin and easily handled by the detaching rolls.

The piecing-up of the detached combed tufts into a continuous combed web, lap, or sheet is effected as usual by rotating the detaching rolls reversely to feed back the preceding detached combed tuft for a part of its length so that the next combed tuft is superposed thereon in partially overlapping relation. Departing from prior practice, however, each successive combed tuft is overlapped for more than half of its length onto its immediately preceding tuft so that the resulting combed web at all points in its length is made up of at least two superposed combed tufts. Thus, with the parts set to produce a combed tuft of the length stated, the detaching rolls are arranged to rotate reversely for a distance of surface travel of around 4 inches, producing an exactly corresponding extent of feed-back of the combed web and a roughly corresponding extent of overlap of the successive combed tufts as each is superposed thereon. For example, with a $5\frac{1}{4}$ inch length combed tuft, and an overlap of approximately 4 inches of each of such tufts upon its preceding tuft, a multiply combed web such as shown diagrammatically in Fig. 12 is formed, which is actually 4 plies thick at all points in its length. Fig. 13 shows diagrammatically how this is done, with the head and tail ends of the first combed tuft indicated at a, a, of the second at b, b, etc. In the phase illustrated, the tail end of the last detached tuft

e, e, has risen from its point X of maximum feed-back, and the combed fringe is being drawn out prior to detaching. However, since the fiber density falls off at each end of each combed tuft, and the end-portions taper off over an extent of an inch or so at each terminus of the combed tuft to end in a feather edge, the leading tapered end-portion of each tuft, at the top surface of the combed lap, is balanced or equalized at the bottom surface of the lap by the equivalent trailing tapered end-portion of a preceding combed tuft having a reverse taper, the two tapered end-portions together making up a thickness which is substantially the equivalent of that of the intermediate portions of any one of the combed tufts. Between these two tapered end-portions lie the full-thickness intermediate portions of at least two other combed tufts, so that the resulting combed web is made up of the equivalent of three full-thickness combed tufts at all points in its length, as in Fig. 12. This may be increased to four or more as indicated in Fig. 13. Thus the combed web is given a substantially uniform fiber density in all sections of its length in the act of piecing up the successive combed tufts, which uniform fiber density once achieved becomes a permanent attribute of the sliver formed by condensing the combed web as it leaves the pan, and persists throughout the drawing and all subsequent processes including the weaving, producing a more uniform and hence stronger yarn for the same count and staple and a stronger, smoother, and more durable fabric. The uniformity initially imparted to the sliver eliminates or greatly reduces the need for the conventional manifold doublings and the multiplicity of draftings which such doublings impose in the spinning, in the effort to fill in and compensate for the thin places in the sliver created by the manner of piecing up employed in prior combers and resulting in a combed lap characteristically banded by alternate thick and thin places. It is not necessary to match up the leading end of one combed tuft in vertical line with the trailing end of the third preceding or any other tuft, since the multiply nature of the combed lap renders the percentage variation of total fiber density much lower at the beginning and end of each tuft, especially in view of the prolonged extent of the tapering end-portions effected by the present machine, than in the prior combed lap with its alternate one-ply and two-ply construction.

Front top detaching roll 10 serves to aid the other two rolls in pressing each succeeding combed tuft into adherence to the preceding tuft, and in consolidating the superposed tufts into a strong and coherent lap. Also, working with rear top roll 8 it shapes each successive tuft to the curvature of bottom roll 7, thereby imparting a curved set to this and the underlying preceding tufts which causes them to follow closely the surface of bottom roll 7 as in Fig. 13 when fed back for piecing up, so as to tend to keep them out of contact with combing cylinder 1 and prevent stripping off of the latest tuft or robbing of fiber therefrom by the needles or other parts of this cylinder, and thus obviates the necessity to give the rear top roll a rolling bodily movement back and forth on the bottom detaching roll. As the drafting and detaching rotation of bottom roll 7 forwardly is effected at very high speed and occupies less than $\frac{1}{4}$ of the machine cycle, the balance of the machine cycle is available and is used for the feed-back, achieving an easy

movement which lets the fed-back tufts follow the surface of roll 7 closely, and incidentally reduces the jerk on the combed web in the pan which has resulted in pulling it apart at this point in prior machines.

The novel housing 9 which surrounds the combing cylinder 1 from about the level of its axis downward and which also encloses stripping brush 5 performs an important part in making possible the exceptionally long feed-back without tearing or robbing of the combed lap by the combing cylinder. Housing 9 fits very closely about both ends of combing cylinder 1 and extends into close proximity to the surface of such cylinder at the rear thereof, while its front wall stands close to the fluted surface of detaching roll 7 and in the vertical plane of the axis of the latter. Inside this housing and extending from end to end thereof is mounted a shield or baffle 139 which has its top edge in close proximity to the surface of combing cylinder 1, but spaced away from the surface of bottom detaching roll 7 and from the front wall of housing 9 sufficiently to afford a clear passage between it and such roll, and also the said front wall, for the recoiling combed tufts when fed back for piecing up. Air is exhausted continuously from within housing 9 during the operation of the machine by means described hereinafter, and the arrangement of the housing causes practically all the make-up air to enter as a continuous downdraft between combing cylinder 1 and detaching roll 7. The shield 139 diverts this downdraft away from the surface of combing cylinder 1 and forward beneath detaching roll 7 to descend between the shield and the front wall of housing 9, so that as shown in Fig. 13 the fed-back combed tufts are held against the surface of detaching roll 7 nearly to the point where such surface passes the top of the front wall of housing 9, and thence slant forward below detaching roll 7. Thus is made possible the extremely long feed-back of the rear end of the combed tuft to a point below the horizontal plane of the axis 2 of the combing cylinder, required in accordance with the invention, without danger of the terminal combed tuft being torn off or robbed of fiber through engagement with the combing cylinder. This is aided by locating the bottom detaching roll 7 far enough forward so that it does not overhang the combing cylinder 1. The downdraft, as heretofore and as noted, also disposes of fly produced during the combing and detaching, and a large part of the short fiber, neps, trash, etc., combed out by the top comb. Further to prevent disturbance of the fed-back combed tufts, a horizontal extension 141 of shield 139 extends throughout the length of housing 9 with its edge close to the line of contact between combing cylinder 1 and brush 5, and the lower edge of shield 139 is extended horizontally rearwardly at 143, to restrain the air currents produced by the rotation of brush 5.

The drive for the rock shaft 13 which effects the actuation of the swing frame, the nippers, the feed roll, the top comb and the lap rolls in the creel is greatly simplified, thereby reducing the cost of construction, facilitating its operation, setting, adjustment and servicing, and reducing wear. It comprises an arm 145, Fig. 6, keyed and also clamped by screw 147 to rockshaft 13 within the gear box 149 at the driving end of the machine, such arm having at its opposite end a cam-follower 151 working in a cam groove 153 in the outward face of a large spur gear 155 mounted on main shaft 2 on which the several combing

cylinders 1 are fixed. This large gear is driven by a pinion 157 on a jackshaft 159 driven by a pulley 161 outside the gear box 149 and connected by belt 171 to pulley 173 on the shaft of the driving motor 175. The cam path 153 is shaped to hold the swing frame at its rearmost position for 90° of the rotation of combing cylinder shaft 2, during which period the needles of the half-lap on such cylinder are combing the fringe held by the nippers, and thereafter to swing the swing frame forward moderately rapidly through the major portion of its swing and then slowly for the final part of its swing to feed the protruding fibers of the fringe progressively into the nip of the detaching rolls, such action occupying 120° of the cycle. There after the cam moves the swing frame rearwardly through an interval of 150° to its starting point.

Adjustment of the closeness of approach of the nipper jaws, carried by the swing frame, to the nip of the detaching rolls to determine the length of fiber desired to be combed out and cast down as waste is effected simultaneously for all the heads of the machine by loosening nut 162 on the threaded end of the pivot 163 on which cam-follower 151 is rotatably mounted, and then shifting pivot 163 in the desired direction along slot 165 by means of opposing set screws 167, with subsequent re-tightening of nut 162. Adjustment of the individual swing frames of the several heads is effected through use of the set screws 23 as previously explained. Ordinarily this single simple change of the position of pin 163 in its slot in arm 145 is the only adjustment needed to change the setting of the entire machine to comb different lengths of fiber or to throw down different percentages of waste. As is obvious, it is impossible as a practical matter to get the swing frame out of time with the half-laps on the combing cylinders.

The drive for the detaching rolls is likewise greatly simplified. It comprises a face cam 169 bolted to the inward side of large gear 155 by cap screws 177 passing through concentric slots 179 permitting change of its angular relation to the main gear, so as to adjust the timing of the detaching rolls. In the path 181 formed in the face of this cam runs a cam-follower 183 which is fixed on a stud 185, Figs. 8, 10 and 11, of a plate 187 which has six studs 189 equally dispersed concentrically around a central hub 191 by means of which latter it is mounted for rotation on a stud 192 affixed to end-plate 194 of the gear box by suitable bolts, the plate 187 being confined between a shoulder on the stud and a retaining disk 196 affixed to the end of the stud by a screw. On the hub 191 of plate 187 is mounted a sleeve gear 193 having a larger spur gear 195 formed on one end thereof and a smaller spur gear 197 at the other, the latter comprising the sun gear of a planetary unit, and between the two gears a hub 199 on which rotates the web 201 of a ring gear 203 having both internal and external teeth, the ring gear being mainly carried on ball bearings 204 in a raceway in plate 187. Small pinions 205 comprising the planetary gears of the unit rotate freely on the six studs, and mesh with both the internal teeth 207 on the ring gear and also with the small spur or sun gear 197 of the sleeve gear, so that if ring gear 203 were held from rotation while plate 187 is being oscillated about the axis of its hub 191 for 90° by cam 169, double the motion in the corresponding directions would be imparted to the sleeve gear 193 and through the large gear 195

thereon to a gear 209 fixed on the end of a shaft 211 extending throughout the length of the machine and carrying the bottom detaching rolls 7 of all the combing heads, thus rocking the detaching rolls back and forth through 180° or more in each direction. But this rocking movement is modified by a continuous rotation imparted to ring gear 203, through a train of gearing comprising a pinion 213 engaging the external teeth of ring gear 203 and a larger gear 215 integral with pinion 213 but spaced away from it axially by a distance of several inches, which large gear is driven by a pinion 217 fixed on the main or combing cylinder shaft 2. Integral gears 213, 215, are mounted on a stud 219 fixed in a plate attached to the inward wall of the inner end plate 194 of the gear box 149. This constant rotation of the ring gear adds about an inch to the distance traveled by the detaching roll in its forward direction of rotation, while drawing out and detaching the tuft, and subtracts this same amount from the motion otherwise imparted by cam 169 to the detaching roll in the reverse movement for piecing up. This is accomplished by members which remain constantly in engagement, instead of through clutches or other parts which must be disengaged and reengaged during each machine cycle as heretofore in certain instances, with resulting wear and tear, noise, and loss of setting. The only adjustment required in the present structure is that of the angular position of cam 169 upon large gear 155, used as noted to time the movements of the detaching rolls to that of the swing frame 15.

The drive for the creel rollers 101 comprises a ratchet gear 223, Figs. 5 and 7, within the gear housing and fixed on the end of a shaft 225 extending throughout the length of the machine and carrying the front creel rolls 101. An arm 227 fixed on rockshaft 13 carries a pivoted gravitating pawl 229 having at its extremity a transverse edge which advances the ratchet each time the rockshaft swings the swing frame forwardly. The pivot connecting the pawl to arm 227 is adjustable radially in a slot in such arm to vary the speed of the creel rolls. The shaft supporting the rear creel roll 101, Fig. 3, is connected by chain 231 and suitable sprockets to shaft 225 to turn in unison therewith.

The stripper brush 5 is driven by chain 233, Figs. 5 and 7, and sprockets 235 and 237 respectively fixed on jackshaft 159 and on full-length shaft 239 on which the brushes are mounted.

With the drives for all the foregoing parts simplified and rendered so compact as to be housed in a gear box occupying only about 12 inches of the length of the machine, it becomes possible for the first time, so far as I am aware, to provide continuous lubrication for all parts occupying such box. This is effected by constructing the lower part of the box 149 to serve as an oil sump, in which one or more inches of oil are constantly maintained. An oil pump having a cylinder 241, Fig. 6, mounted on the bottom of the box with its intake port below the level of the oil in the sump pumps such oil up through a pipe 243 and discharges it in jets of substantial force from the end 245 of such pipe against rockshaft 13 at midwidth of the box, so that the oil constantly spatters over all moving parts within the box and drips onto such parts from the rockshaft, keeping all parts continuously and thoroughly lubricated and in particular avoiding the wear of the cams actuating the detaching rolls and other parts effecting the detaching and

piecing up, which has been so troublesome in the past. A pin 247 adjustably fixed in a slot in a short arm 249 extending from the hub of arm 145 is joined by connecting rod 251 to piston 253 of the pump to actuate the latter.

The novel and improved facilities for automatically salvaging and disposing of the waste produced in the operation of the machine involve the use of a heavy member 255, Figs. 1 and 3, of inverted U-section as the frame or backbone of the whole machine. By the simple expedient of closing the ends of this member, herein by integral webs 257, and closing the bottom by lengths of sheet metal 259 turned up at the sides and fastened on by screws, this backbone is converted into a waste duct. Large inlet ports 261 are formed in the top wall of member 255 within each housing 9 of each combing head, and a plate 263 which is substituted in one spot for the sheet metal closure means 259 on the bottom of channel member 255 has a central aperture equipped with a collar 265 in which is secured one end of a conduit 267 the other end of which is connected to the axial intake port of a centrifugal blower 269 direct-connected to the shaft of motor 176. The discharge port of the blower has a conduit 271 which leads directly to a waste bin (not shown) or other suitable collection point for the waste from a group of combers. The result is that all waste removed from the half-lap by stripper brush 5 and thrown off within housing 9, as well as the fly produced in the combing which is all drawn down by the draft induced between combing cylinder 1 and detaching roll 7 by blower 269, are continuously carried off through the ports 261 from each combing head, through the duct formed within backbone member 255, through conduits 267 and 271, and disposed of in the waste bin automatically. In this manner the expense and nuisance of providing and attending to individual catcher boxes behind each head, or the more objectionable practice of letting the waste pile up on the floor beneath each head in unsightly manner, with added difficulty of handling, risk of contamination of the waste, and creation of a fire hazard, are completely avoided, the elimination of manual doffing representing a very material saving in the cost of operation.

To determine the percentage of waste being removed by a particular combing head, a sheet of wire screening 272 is inserted through a narrow slit 273, Fig. 3, left between the bottom of housing 9 and the top of channel member 255, at midlength of the back wall of housing 9, so that the screen completely covers inlet port 261 in member 255. This is withdrawn after a few minutes, and the amount of waste caught by the screen is checked against the weight of the stock fed to that head in the same interval of time. A hand-hole 275 in the back wall of housing 9, covered by a vertically swinging cover 277, gives access to the housing for cleaning stripper brush 5, and for other purposes.

The drawbox 279 is of any suitable or preferred construction having capacity to handle the increased weight of sliver produced.

The pairs of drawing rolls are driven at successively faster speeds by gear trains of standard or any preferred design taking power from the end of combing cylinder shaft 2. A feature of improvement is that these gears run in oil retained in a sump in the bottom of a gear case 323 having a removable cover provided with a handle, and thus are continuously lubricated.

The calendar rolls 325 which draw the sliver from the pans through trumpets (not shown) are driven from the gears in the box 323 by a shaft extending the full length of the machine beneath sliver table 327.

By reason of the simplified structure a great reduction has been effected in the number of moving parts as compared with prior combers, and at the same time the bearings of the remaining moving parts have been made more accessible and adapted to the use of anti-friction bearings and pressure lubrication fittings, thereby reducing the frequency and effort of lubricating the whole machine, with resultant notable saving in the cost of maintenance and servicing, and in power consumption, in addition to the material reduction in the cost of construction.

The coiler mechanism 329 is of standard or any preferred design, taking its drive from within gear box 323.

While I have illustrated and described certain forms in which the invention may be embodied, I am aware that many modifications may be made therein by any person skilled in the art, without departing from the scope of the invention as expressed in the claims. Therefore I do not wish to be limited to the particular forms shown, or to the details of construction thereof, but what I do claim is:

1. A method of piecing up the detached combed and drafted tufts from a comber head which includes the steps of assembling two successive detached tufts of combed fibers so that each tuft overlaps the other for two-thirds of its length, and applying a third detached tuft of combed and drafted fibers from such comber head so that a line of junction between the first two is located intermediate the length of the third tuft.

2. A method of combing textile fibers which includes the step of piecing up detached combed and drafted tufts by overlapping each successive tuft for at least two-thirds of its length upon the preceding tuft, after the latter has been combed and drafted.

3. A method of combing textile fibers which includes the step of piecing up detached combed and drafted tufts by overlapping the successive tufts so that at least two plies of combed tufts intervene between the head end of one combed tuft and the nearest tail end of a preceding combed tuft.

4. A method of combing textile fibers which includes the step of piecing up detached combed and drafted tufts by overlapping the successive tufts in multiply relation so that the resulting web has at all points a thickness of at least three plies of combed tufts.

5. In a machine for combing textile fibers, in combination, means feeding and combing the fibers, and means including a detaching roll drawing and detaching the combed fibers in tufts, and overlapping the drawn and detached tufts onto each other on the detaching roll into a web which is at least three plies of such tufts thick at all points in its length.

6. In a machine for combing textile fibers, in combination, means feeding and combing the fibers, a detaching roll first drawing and then detaching tufts of fibers, and means feeding the successive combed tufts into overlapping relation on the detaching roll to form a web at least three tufts thick at all points in its length.

7. In a machine for combing textile fibers, in combination, nipper jaws, a feed roll feeding the fibers through the nipper jaws, means combing

the fibers held by the nipper jaws, detaching rolls taking the fibers from the nipper jaws, and means actuating the feed roll and the detaching rolls and imparting a forward surface travel to the latter at least twenty times as great as that of the feed roll and a rearward travel overlapping the successive tufts into a web of at least three plies thick at all points.

8. In a machine for combing textile fibers, in combination, a revolving combing cylinder, a detaching roll rotating on a fixed axis, a housing partially surrounding the combing cylinder, means presenting the fibers to the combing cylinder and then to the detaching roll for the detachment thereby of a combed tuft of fibers, means actuating the detaching roll to feed back a tuft of combed fibers long enough to extend below the horizontal plane through the axis of the combing cylinder, and a shield within the housing in fixed and spaced relation to the detaching roll and the combing cylinder holding the fed-back tuft out of contact with the combing cylinder.

9. In a machine for combing textile fibers, in combination, means feeding a supply of fibers, a combing cylinder, a roll detaching combed tufts of fibers from the supply and feeding them back for piecing up, means creating a current of air between the combing cylinder and the detaching roll, and a baffle also intervening between the combing cylinder and the detaching roll.

10. In a machine for combing textile fibers, in combination, means feeding a supply of fibers, a combing cylinder, a roll detaching combed tufts of fibers from the supply and feeding them back for piecing up, a housing partially surrounding the combing cylinder and the detaching roll, means exhausting air from the housing to create a draft between the combing cylinder and the detaching roll, and means diverting such draft away from the combing cylinder.

11. In a machine for combing textile fibers, in combination, nipper jaws, a rockshaft, means thereon supporting the nipper jaws to swing about the axis of the rockshaft, a top comb swinging about a fixed center apart from the axis of the rockshaft, and means imparting simultaneous swinging movement to the jaws and the comb from the rockshaft.

12. In a machine for combing textile fibers, in combination, nipper jaws, a rockshaft, means on the rockshaft supporting and swinging the nipper jaws back and forth about the axis of the rockshaft as the rockshaft rocks, a top comb swinging about a different fixed center, and a link connecting the comb and the said supporting means and actuating the comb.

13. In a machine for combing textile fibers, in combination, a fixed frame, a rockshaft, means rocking the rockshaft, relatively movable nipper jaws supported by and swung back and forth by the rockshaft, and means on the frame resisting the bodily movement of one of the jaws in the backward and forward directions and thereby causing the opening and shutting of the jaws.

14. In a machine for combing textile fibers, in combination, a fixed abutment, a rockshaft, a frame suspended from and swung back and forth by such rockshaft, a lower nipper jaw in operatively fixed relation on such frame, an upper nipper jaw pivotally mounted on such frame, and means in operative connection with the abutment and with the upper jaw alternately holding back on such jaw as the frame swings forward

and pushing forward on such jaw as the frame swings back, to swing the jaw about its pivot and effect the opening and closing of the jaws.

15. In a machine for combing textile fibers, in combination, a fixed abutment, a rockshaft, a frame suspended from and swung back and forth by such rockshaft, a lower nipper jaw in operatively fixed relation on such frame, an upper nipper jaw, means including an arm mounting the upper jaw pivotally upon the frame, and a link connecting the arm to the fixed abutment and alternately pulling and pushing on the arm to move the upper jaw about its pivot as the frame is moved in alternately opposite directions.

16. In a machine for combing textile fibers, in combination, a combing cylinder, a shaft on which such cylinder is fixed, a detaching roll detaching tufts of fibers combed by such cylinder, a gear train driving the detaching roll from such shaft including a sun gear and at least one planetary gear engaging therewith, cam means on the combing cylinder shaft causing bodily movement of the planetary gear about the sun gear, and a gear coaxial with the sun gear continuously driving the planetary gear.

17. In a machine for combing textile fibers, in combination, a combing cylinder, a detaching roll, means presenting fibers to the combing cylinder and to the detaching roll, and means for rotating the latter alternately in opposite directions including a gear driving the roll, at least one pinion driving the gear, a gear having internal teeth driving the pinion, means driving the internal-toothed gear at constant speed, and means moving the pinion bodily about the axis of the first-named gear alternately in opposite directions.

18. In a machine for combing textile fibers, in combination, a combing cylinder, a detaching roll, means presenting fibers to the combing cylinder and to the detaching roll, and means for rotating the latter alternately in opposite directions including a gear driving the roll, a plate rotatable coaxially with the roll gear, a ring gear having internal and external teeth and rotatable coaxially with the roll gear, pinions on the plate driven by the internal teeth and driving the roll gear, means driving the ring gear at constant speed by engagement with its external teeth, and means oscillating the plate.

19. In a machine for combing textile fibers, in combination, a swing frame, nippers and a feed roll thereon, a rockshaft entirely supporting and actuating the swing frame, a combing cylinder, a rotating shaft on which the cylinder is fixed, a detaching roll, means driving the latter from the cylinder shaft, a cam on such shaft actuating the rockshaft and a second cam on such shaft periodically reversing the direction of rotation of the detaching roll and angularly adjustable about such shaft to vary the timing of this reversal.

20. In a machine for combing textile fibers, in combination, a combing cylinder, a detaching roll, nippers traveling back and forth between the cylinder and the roll, a rockshaft carrying the nippers, a shaft on which the combing cylinder is fixed, a cam on the latter shaft, an arm operatively fixed on the rockshaft, a cam-follower on the arm and actuated by such cam, and means for varying the position of the cam-follower angularly about the rockshaft to determine the closeness of approach of the nippers to the detaching roll.

21. In a machine for combing textile fibers, in combination, multiple comber heads each includ-

ing a combing cylinder and stripping means for the cylinder and a housing enclosing the stripping means and a part of the cylinder, a hollow frame member supporting the comber heads and having a passage communicating with the housing interiors, and air exhausting means connected to the interior of the hollow frame member creating a current of air carrying off via the hollow member the fibers stripped from the combing cylinders.

15. 22. In a machine for combing textile fibers, in combination, multiple comber heads each including a combing cylinder and stripping means for the cylinder and a housing enclosing the stripping means and a part of the cylinder, a hollow frame member supporting the comber heads and having a passage communicating with the housing interiors, air exhausting means connected to the interior of the hollow frame member creating currents of air carrying off via the hollow member the fibers stripped from the combing cylinders, and duct means conducting the air currents and the fibers carried thereby from the several comber heads to a common waste receptacle.

30. 23. In a machine for combing textile fibers, in combination, a combing cylinder, stripping means therefor, a housing enclosing the stripping means and a part of the cylinder, duct means in unobstructed communication with the housing interior, means creating a current of air through the housing and thence through the duct to transport the combed-out-fibers through the duct, and means for temporarily introducing a screen across the path of the air current to determine the amount of fibers being combed out.

40. 24. In a machine for combing textile fibers, in combination, a rockshaft, means for rocking the rockshaft, a swing frame fixed on and swung back and forth by the rockshaft, nippers and a feed-roll carried by the swing frame and actuated by the swing thereof, lap rolls, means driving the lap rolls from the rockshaft, and a swingably mounted top comb also swung back and forth by the swing of the swing frame.

50. 25. In a machine for combing textile fibers, in combination, a combing cylinder, nipper jaws gripping the fibers at the points where the fibers emerge from the jaws, detaching rolls comprising opposed rolls of which the bottom roll is substantially twice the diameter of the other roll, and means driving the detaching rolls to effect a draft on the order of 15 or more times on the tuft being detached reducing the weight of fiber handled at a given instant by the detaching rolls and to effect an overlap of each tuft on the preceding tuft exceeding one-half of the length of the tuft being detached, whereby the combed lap is composed of at least three piles of combed tufts at all points in its length, the detaching rolls feeding back the overlapping combed tufts through their nip for at least two-thirds of the length of the final tuft and the bottom detaching roll making continuous contact with the portions of the tufts which have been passed back through such nip for at least one-half the full extent of such feed-back to support the combed tufts thus fed back through the nip.

70. 26. In a combing machine for textile fibers, in combination, a combing cylinder, nippers which grip the fibers of a supply lap at the points on the nipper jaws which approach closest to the combing cylinder, a combing cylinder combing substantially the entire protruding

21

length of each fiber extending from the nipper jaws producing a corresponding length of combed fringe extending from the jaws, a fixed top detaching roll, a bottom detaching roll substantially twice the diameter of said top roll providing extended support for the fed-back tufts, means for creating and directing a flow of air holding the fed-back tufts against the surface of the bottom detaching roll and clear of other surfaces, and driving means for the detaching rolls producing a draft of each combed tuft during detaching thereof on the order of 15 or more times and producing a reverse rotation of said detaching rolls, following detaching, exceeding one-half of the forward rotation effecting an overlap of each tuft on the preceding tuft of more than two-thirds the tuft length.

27. A method of combing textile fibers which includes the steps of subjecting the fibers of a supply lap having a weight of approximately 115 grains per yard per inch of lap width first to combing, then to a draft by detaching rolls on the order of 20 or more times the length of feed per nip of the supply lap, and to detaching and piecing-up operations.

28. The improvement in the combing of textile fibers by the process of combing, drawing, detaching, and piecing up a web of fibers which includes the steps of combing fibers of a supply lap having a weight of approximately 115 grains per yard per inch of lap width, drafting the combed fibers on the order of 20 or more times the length of feed per nip of the supply lap, detaching the combed and drafted fibers in tufts at the completion of the drawing, and piecing up the detached tufts into a web not less than three tufts thick at all points in its length.

29. The improvement in the combing of textile fibers by the process of combing, drawing, detaching, and piecing up a web of fibers which includes the steps of combing fibers of a supply lap having a weight of approximately 115 grains per yard per inch of lap width, drafting the combed fibers on the order of 20 or more times the length of feed per nip of the supply lap, detaching the combed and drafted fibers in tufts at the completion of the drawing, feeding back the terminal tuft for about 4 times the average length of the fibers being combed, supporting such tuft for a distance of about 3 times such fiber length, and holding such tuft against its support by a current of air.

30. A method of combing textile fibers which includes the steps of combing, drawing, and detaching the fibers in tufts having a length of about 5 times the average length of the fibers being combed, piecing up the tufts by feeding back the terminal tuft for a distance of about 4 times such average length, supporting the fed-back tuft upon a surface extending lengthwise of the tuft throughout a distance of about 3 times such average length, and holding the tuft against such support by a current of air.

31. The method of piecing up the detached combed and drafted tufts from a comber head which includes the steps of feeding back the pieced-up tufts for a distance exceeding the length of the component fibers, and preventing the fed-back terminal tufts or parts thereof from falling off or being torn off, by holding the latter tufts against a supporting surface for a distance exceeding the average length of the component fibers by a directed flow of air. 75

22

32. In a machine for combing textile fibers, in combination, means feeding and combing the fibers, and detaching and piecing-up means comprising a bottom detaching roll and two top detaching rolls pressing against the bottom roll, the latter being of substantially twice the diameter of a top roll and supporting the combed lap for a length exceeding twice the average length of the fibers when such lap is fed back over the bottom roll.

33. In a machine for combing cotton fibers, in combination, means feeding and combing the fibers, and detaching and piecing-up means comprising a bottom detaching roll and a top detaching roll pressing against the bottom roll, the latter being of a circumference greater than 4 times the average length of the cotton fibers being combed and providing extended support for the combed lap of fibers when fed back thereover.

34. In a machine for combing textile fibers, in combination, means feeding a supply of fibers, a combing cylinder, a roll detaching combed tufts of fibers from the supply and feeding them back for piecing-up, means creating a current of air between the combing cylinder and the detaching roll, and means directing such air current over at least a portion of that surface of the detaching roll over which the combed tufts are fed back.

35. In a machine for combing textile fibers, in combination, means feeding a supply of fibers, a combing cylinder, a roll detaching combed tufts of fibers from the supply and feeding them back for piecing-up, a housing partially surrounding the combing cylinder and the detaching roll, means exhausting air from the housing to create a draft between the combing cylinder and the detaching roll, and means substantially confining such draft to a path of travel over that surface of the detaching roll over which the combed tufts are fed back.

ODUS C. HINSON.
